Sharples Corporation, Philadelphia, Pa., a cor-
poration of Delaware

Application February 4, 1943, Serial No. 474,641

2 Claims. (Cl. 210—76)

The present invention pertains to centrifugal machines designed to effect separation of adhering liquid from solids by straining of the liquid from the solids under the influence of centrifugal force. It consists in an improvement of the straining element or screen of Brewer Patent 2,271,493, as illustrated particularly in Figures 4, 12 and 13 of that patent.

The features of the present invention pertain to details of improvement of the screen which provide increased strength and flexibility. By the use of these features, the danger of breakage is minimized because of the increased strength, and the danger that the screen joint may project inwardly from the circumference of the remainder of the screen is also minimized, thereby minimizing the chance that this joint may be damaged by impact against the tool periodically used to dislodge the collected and dehydrated solids. These advantages are attained by securing the ends of the circumferentially extending screen to a relatively flat metal plate by a metal union, as more specifically set forth hereinafter.

Further features and advantages of the invention will be evident from the following detailed description when read in the light of the attached drawing, in which,

Figure 1 is a longitudinal cross section through a centrifugal rotor and screen, illustrating the manner in which the screen is used.

Figure 2 is a detailed plan view of the screen joint, and

Figure 3 is a developed cross section on the line 3—3 of Figure 2.

Referring to Figure 1 of the drawing, the centrifugal rotor 10 is provided with a circumferential wall 11 having perforations 12 for discharge of liquid separated from solids by rotation of the rotor. The circular woven wire screen of the invention fits snugly within the inner surface of the circumferential wall 11. The details of construction and operation of the machine other than those pertaining to the screen may be similar to those of Brewer Patent 2,271,493, or of any other construction used in the art of hydro-extractors. In the Brewer patent, the cylindrical screen is formed by welding the ends of the warp wires of a woven wire screen together, after bending such a screen into cylindrical form. Such an arrangement, while it provides important advantages over the art prior to the Brewer patent, as pointed out in the specification of that patent, is subject to the disadvantage that the welded joint is sometimes weaker than the remaining portions of the screen, and that this joint, due to the fact

that it has less flexibility than the remainder of the screen, sometimes projects to a point slightly within the inner curved surface of the remaining portions of the screen, with the result that damage occurs by reason of contact of this joint with the dislodging tool. These disadvantages are avoided with the screen construction of the present invention.

As illustrated in Figures 2 and 3 of the drawing, 10 the screen of the invention consists of a plurality of interwoven warp wires 13 and weft wires 14.

The construction of the screen of the invention may be best understood by a preliminary discussion of the preferred method of making it. The 15 two end weft wires of a flat strip of screen containing warp and weft wires 13 and 14 are first removed to provide substantial lengths of warp wires extending as indicated at 15 beyond the endmost weft wires. The screen is then bent into 20 circular shape, and the extending warp wires from each end of the screen are straddled onto a metal plate 16 so that the plate occupies the position vacated by the removal of the weft wires. The metal plate should be relatively thin in order 25 that the total thickness of the wires plus the plate is substantially the same as the maximum thickness of the screen portions adjacent the zones at which the warp wires cross the weft wires. The warp wires are then connected to the plate 16 by 30 a metallic union, such as welding. The metal plate 16 should preferably be relatively flexible in order that it may assume the shape of the surrounding circumferential wall 11 when inserted within this wall and subjected to centrifugal force 35 by rotation of the rotor 10. If the plate 16 is not sufficiently flexible to assume this shape because of the natural stress imposed in placing the screen within the wall of the rotor or because of centrifugal force, it should be curved to conform to 40 the shape of the rotor in which it is to be used, before placing it within the rotor wall. As illustrated in the drawing, the alternate wires from opposite ends of the screen which lie on the same side of the plate 16 preferably intermesh somewhat at their ends.

In operation, when a rotor containing the improved screen of the invention is used in effecting centrifugal removal of liquid from solids, liquid removed from the solids lying within the portion 50 of the straining surface overlying the plate 16 will not, of course, be immediately removed, but this liquid will flow circumferentially along the plate 16 during rotation of the rotor until it reaches a pervious portion of the screen and is removed through one of the outlets 12.

Various modifications are possible within the scope of the invention, and we do not therefore wish to be limited except by the scope of the following claims.

We claim:

1. In a centrifugal machine for separating liquids from solids, the combination comprising a rotor and a circumferential woven wire screen within said rotor, said screen comprising a plurality of laterally spaced warp wires bent to conform to the shape of said rotor and having their opposite ends brought into proximity with each other, and a plurality of weft wires extending across said warp wires to form the desired woven structure; and a relatively wide plate, the surface of which is adapted to lie parallel to and adjacent the inner surface of the rotor and having a thickness not substantially greater than the greatest diameter of said weft wires, said plate extending in a direction substantially parallel to the weft wires and between the oppositely extending ends of said warp wires and secured thereto to form a joint therebetween devoid of weft wires, the respective warp wires of each end of the screen being bent so that alternate wires extend over the edges of said plate and lie on opposite sides thereof, and said alternate oppositely extending wires being secured respectively to said opposite sides of said plate.

2. In a centrifugal machine for separating

liquids from solids, the combination comprising a rotor and a circumferential woven wire screen within said rotor, said screen comprising a plurality of laterally spaced warp wires bent to conform to the shape of said rotor and having their opposite ends brought into proximity with each other, and a plurality of weft wires extending across said warp wires to form the desired woven structure; and a relatively wide plate, the surface of which is adapted to lie parallel to and adjacent the inner surface of the rotor and having a thickness not substantially greater than the greatest diameter of said weft wires, said plate extending in a direction substantially parallel to the weft wires and between the oppositely extending ends of said warp wires and secured thereto to form a joint therebetween devoid of weft wires, the respective warp wires of each end of the screen being bent so that alternate wires extend over the edges of said plate and lie on opposite sides thereof, the alternate oppositely extending wires being secured respectively to said opposite sides of said plate, and said alternate wires from one end of said screen which are secured to one side of said plate intermeshing with ends of similar wires extending in an opposite direction from the opposite ends of said screen on the same side of said plate.
